UNITED STATES PATENT OFFICE.

ALEXANDER W. CARROLL, OF ELIZABETH, NEW JERSEY.

MELTING-FURNACE.

1,182,893.

Specification of Letters Patent.

Patented May 16, 1916.

Application filed July 7, 1915. Serial No. 38,425.

To all whom it may concern:

Be it known that I, ALEXANDER W. CARROLL, a citizen of the United States, and a resident of Elizabeth, Union county, State 5 of New Jersey, have invented certain new and useful Improvements in Melting-Furnaces, of which the following is a description.

My invention relates to melting furnaces 10 and particularly to furnaces for melting metals such as brass.

So far as I am aware, there has, up to the present time, been no successful gas furnace built for melting brass or similar metals.

15 The fuel generally used for this purpose is coal, and the furnaces employed are usually of rather crude construction, including merely a suitable grate for supporting the fuel, and the necessary draft appliances.

20 The coal must be carefully introduced into the furnace, as it forms the support for the pot containing the metal to be melted. Since these pots come into direct contact with the burning coal, they often become fractured, 25 thus causing the loss, not only of the pot, but also of a considerable portion of the metal contained therein. Because of the above considerations, the operation of the melting furnaces now in general use is at 30 best slow and inefficient.

An object of my invention is to provide a melting furnace occupying approximately the same space as a coal furnace, but designed to use gas as a fuel, and so arranged 35 that the pots containing the metal are heated evenly at all points, without danger of being fractured.

Another object of my invention is to provide a furnace which shall require a comparatively slight amount of care in the operation thereof, and which may therefore be operated more frequently and more efficiently than the furnaces now in general use.

Another object of my invention is to provide means for introducing the combustible gases into the combustion chamber of the furnace in such a direction that they are given a whirling movement within the chamber, and to so arrange the flue as to 50 produce a down draft in the chamber.

Other objects of my invention will appear more fully in the specification and claim which follow.

Referring to the drawing, Figure 1 represents a plan view partially in section of a portion of a battery of furnaces embodying

my invention; Fig. 2 is a front view thereof, partly in section; Fig. 3 is an end view thereof, partly in section, and Figs. 4, 5 and 6 are views substantially similar to Figs. 1, 2 and 3 respectively, but showing a slight modification of my invention.

Referring to the drawing, 10 represents the combustion chamber of my improved furnace. This combustion chamber is preferably divided into two concentric compartments such as 11, 12 by a wall indicated at 13, which may be of any heat resisting material. This wall, as shown, does not extend to the top of the combustion chamber, 65 but permits of communication between the two compartments 11, 12.

In the embodiment of my invention disclosed in Fig. 1, I have shown the means for supporting the pot or container 14 to 75 comprise the cross-shaped member 15 clearly shown in Fig. 1, which provides communicating passages 16 from the inner compartment 11 into the flue 17. This flue 17 extends longitudinally of the battery of furnaces beneath the several combustion chambers and communicates with the stack 18 which is provided with a suitable damper 19. This arrangement of the flue, as is readily seen, produces a down draft in each of 80 the combustion chambers.

Located within the flue 17 and running longitudinally thereof are the pipes or conductors 20, 21 which in this case conduct gas and air respectively to a common conductor 90 or conductors such as 22 which in turn communicate with the combustion chamber of each furnace. I preferably arrange these conductors 22 to enter the combustion chamber at an angle, so that the gases which are 95 introduced into the combustion chamber are given a whirling movement. I preferably also use a plurality of these conductors 22, in order that the heat due to the combustion of the gases may be distributed as evenly as 100 possible throughout the chamber. By passing the conductors 20, 21, through the flue 17, the gases carried by the conductors are effectually heated before they are introduced into the combustion chambers.

105 In the embodiments shown in Fig. 1, I have illustrated the conductors 22 as communicating with the outer compartment 12 of the combustion chamber, so that the combustible gases which enter through the conductors 22 into the combustion chamber, pass in a whirling movement through the

outer compartment 12 and thence over the wall 13 and down through the compartment 11 into the flue 17. By this arrangement, it is apparent that while all the heat is maintained within the combustion chamber, the initial flame of the burning gases, which is most detrimental to the pot, does not come in contact with the pot. It is apparent also that the burning gases are drawn down through the compartment 11 upon all sides of the pot, thereby heating it at all points equally.

I preferably provide each furnace with a cover, such as shown at 23, whereby access may be had to the interior of the furnace when desired. I also preferably provide each furnace with a removable pan, such as indicated at 25, which fits within a recess 26 formed below the combustion chamber 20 of each furnace for catching the metal escaping from the pot or container in case the pot or container should break. This recess 26 may be closed by means of a door 27 of any suitable type.

The main difference between the modified form of my invention shown in Figs. 4, 5 and 6, and the form shown in Figs. 1, 2 and 3, is that in the modified form the gases are introduced into the inner compartment, 30 and thence pass into the outer compartment, instead of first entering the outer compartment and passing from there into the inner compartment. Referring to Figs. 4, 5 and 6, it is seen that in the modification, the outer compartment 12' communicates with the flue 17' and thus has a down draft produced therein. The inner compartment is closed to the flue 17' during the operation of the device, by some suitable means, such as the block 28, upon which the pot or container 14' is adapted to rest. Beneath this block 28 is an opening 29 into the flue 17', whereby, when the pot or container breaks, the block 28 may be removed and the material from the pot may pass through the opening 29 into the pan 25' and thus be readily recovered.

The conductors 22' in this modification communicate with the inner compartment 50 11', tangentially, so that the gases which are introduced into the compartment 11' are given a whirling movement. These gases also move upward around the pot 14' and thence pass over the wall 13' into the compartment 12' and finally out through the flue 17' to the stack.

Since it requires very little time to prepare my improved furnace, for melting a charge of material, I am able to take more "heats" than is possible with furnaces using coal as a fuel, and for this reason I find it advantageous to make use of some suitable means for artificially cooling the furnace. With this end in view, I have shown my furnace provided at the top with a water jacket 30.

Reference numerals 10', 18', 19', 20', 21', 23', 25', and 27' in Figs. 4, 5 and 6, apply to parts similar respectively to parts 10, 18, 19, 20, 21, 23, 25 and 27, of Figs. 1, 2 and 3. 70

The method of operation of my improved furnace should be obvious from the above.

The advantages of my furnace over those heretofore in use should also be readily recognized. For example, I effect considerable economy in operation by eliminating the necessity of skilled labor, and by reducing the possibility of fracturing the pots. Also I make it possible to take more "heats" in a given time in one furnace, than has been possible heretofore, thus reducing the overhead expense. 75

It is to be understood that I do not wish to limit myself to the disclosure herein, since obviously many changes may be made in the apparatus described, by those skilled in the art, without departing from the spirit of my invention. 85

What I claim is:

In a melting furnace, the combination of 90 a combustion chamber, a wall dividing the lower portion of said chamber into two concentric compartments communicating at the top, means located in the inner compartment for supporting a container for the material to be melted, conductors for introducing combustible gases into one of said compartments, in such a direction that they are given a whirling movement, and a flue located beneath said chamber and communicating with the other compartment and adapted to produce a down draft therein, said conductors being located in said flue, whereby the gases are heated before they are introduced into said chamber. 95

In testimony whereof I have signed this specification in the presence of two subscribing witnesses.

ALEXANDER W. CARROLL.
